UNITED STATES PATENT OFFICE.

ERNEST W. CAMPBELL, OF PROVIDENCE, RHODE ISLAND, ASSIGNOR TO THE
CAMPBELL-METCALF SILVER COMPANY, OF SAME PLACE.

DESIGN FOR A SPOON.

SPECIFICATION forming part of Design No. 23,097, dated March 6, 1894.

Application filed January 27, 1894. Serial No. 498,254. Term of patent 3½ years

To all whom it may concern:

Be it known that I, ERNEST W. CAMPBELL, a citizen of the United States, residing at Providence, in the county of Providence and State of Rhode Island, have invented and produced a new and original Design for Spoons, of which the following is a specification.

The design is more especially intended to be embodied in a souvenir spoon or similar article for the State of California and commemorative of the "Mid-Winter Exposition," though it is not restricted in this particular.

The design is arranged and borne by the obverse and reverse sides of the handle.

15 In the accompanying drawings Figure 1 represents the obverse side of a spoon embodying my design and Fig. 2 the reverse side.

20 The outline of the handle is somewhat irregular although substantially retaining the general or conventional taper form. On the obverse side of the handle the design includes the representation of the rising sun partially

surrounded by scroll work; below this are arranged representations of various kinds of 25 fruits. At a lower point is a representation of a bear, while the shank of the handle near its junction with the bowl carries the representation of a pioneer gold miner.

The design includes the representation on 30 the reverse side of the handle the "Cliff House," San Francisco, "San Gabriel Mission," Los Angeles, the "Golden Gate" and the "Lick Observatory," all combined with suitable scrolled devices. At intervals spaces 35 are provided, as at *a*, to receive suitable inscriptions.

I claim—

35 The design for a spoon or similar article herein shown and described. 40

In testimony whereof I have affixed my signature in presence of two witnesses.

ERNEST W. CAMPBELL.

Witnesses:

GEO. H. REMINGTON,
IDA M. WARREN.
